UNITED STATES PATENT OFFICE.

LILLIAN FORD TRAVER, OF SAND LAKE, NEW YORK.

GARMENT.

Application filed October 5, 1926. Serial No. 139,649.

Reference may be had to the accompanying drawings, and the reference characters marked thereon, which form a part of this specification. Similar characters refer to similar parts in the several figures therein.

The principal object of the invention is to provide a nether garment, or the nether portion of a combination garment with a better fitting and more comfortable crotch and 10 groin portion.

Other objects will appear in connection with the following description.

Fig. 1 of the drawings is a view in front elevation of a combination garment embodying my invention.

Fig. 2 is a rear elevation of the same.

Fig. 3 is a plan view of one of the two-piece gussets used in forming the crotch and groin portions of the garment.

Fig. 4 is a cross section of the same on a larger scale taken on the broken line 4—4 in Fig. 3.

Fig. 5 is a plan view of the more acutely curved gusset member.

Fig. 6 is a similar view of the less acutely curved gusset member.

Fig. 7 is a plan view illustrating the manner in which the gusset members are stitched together.

Fig. 8 is a cross section taken on the broken line 8—8 in Fig. 7.

Fig. 9 is a plan view of the two-piece gusset shown in Fig. 3 with the straight line edges of the two members of the gusset drawn into alignment as for attachment to one of the straight line edges of the back opening in the body of the garment.

Fig. 10 is a plan view of a broken-away portion of the garment showing the back opening in the body of the garment with the inner double gusset attached thereto.

Referring to the drawings wherein the invention is shown in preferred form, the body of the garment includes, a front, 1, and a back, 2, terminating at the lower end in legs, 3, seamed along their inner sides at 4.

The body of the garment is cut at the front on convergent lines, 5, from the upper terminations of the respective inner leg 50 seams to a point, 6, substantially above the crotch, 7, of the garment.

The front and back of the garment may be made of a single piece of fabric or of separate pieces united by side seams, 8, and the garment may be provided with sleeves, 9, if desired.

I have shown the garment in the preferred form of a combination garment for which the invention is particularly adapted and the upper portion of the garment may be worn as an outer shirt while the nether portion is shown as underdrawers.

If desired the body of the garment may be fashioned as indicated by the dotted curved lines, 8^a, in Fig. 2.

The crotch and groin portions of the garment are formed by two overlapping double gussets, 10, 10^a, and 11, 11^a, the members of each of said gussets being joined together by a bulging seam, 12.

The seamed together edges of the two members of each gusset are cut on curved lines, the edge, 20, of the member, 10 or 10^a, which forms the lower inner corner of the gusset being curved to a greater degree than the attached edge, 21, of the other gusset member, 11 or 11^a.

These differently curved edges of the gusset members are stitched together in the manner shown in Fig. 7, the edge of one or both of said members being distorted or shirred sufficiently to cause the corresponding edges of the two members to substantially align with each other.

When the gusset members have been thus stitched together and are opened out, the resultant gusset will bulge or present a fullness along the seam as diagrammatically illustrated in Fig. 4.

The projecting edge, 13, of the gusset member, 10, in Fig. 7 is for the purpose of making a felled seam as shown in Fig. 4.

The gusset members, 10 and 11, are triangular in general form with one side curved as above described.

The double gusset formed as above described has a straight line edge, 14, on the member, 10 or 11, forming an obtuse angle with a straight edge, 15, on the complementary member, 10^a or 11^a, of the gusset, as shown in Fig. 3.

The back of the garment is formed with

2 an opening, 16, the edges of which are cut on straight lines longitudinally of the garment, and when the double gussets are to be attached to the garment, the two edges, 14, 15, and 16, of the double gusset are brought into alinement with each other, and stitched or seamed to one of the straight edges of the back opening, 16, as shown in Fig. 10, in which the inner of the two double gussets 10 is shown attached by stitching, 17, to the right hand edge of said back opening on the inner side of the body of the garment, so that the free edge of the gusset is within the body of the garment.

15 In like manner, the other double gusset is attached to the opposite straight edge of the back opening, 16, on the outer side of the body of the garment as shown in Fig. 2.

The two double gussets are substantially 20 alike in form, overlapping each other and one lapping on the inner side the back of the body of the garment, and the other lapsing on the outer side the body of the garment.

25 The free end of the outer double gusset may be provided with a buttonhole, 18, adapted to engage a button, 19, attached to the back of the body of the garment.

While for certain purposes of my invention 30 the garment may be made of any kind of cloth, I prefer to make it of textile fabric and have indicated by shade lines on certain figures of the drawings the direction of the interwoven threads.

35 When made of such textile fabric with the threads arranged as shown, the straight edges, 14 and 15, will be parallel with the longitudinal threads of the fabric, and therefore parallel with the longitudinal 40 threads of the body and the fabric along the straight edges of the back opening, 16.

In thus cutting the gusset members, the seamed-together curved edges, 20 and 21, of the gusset members, will be cut on the bias, thus facilitating such stretching or distortion of the fabric as may be necessary in bringing said differently curved edges into substantial alinement in stitching the same together.

45 The front ends of the respective double gussets are stitched to the respective convergent front edges, 5, of the garment, as shown in Fig. 1.

The crotch or groin portions of the garment 50 are thus provided with a fullness or capacity, due not only to the triangular form of the gusset members, 10 and 10^a, but also to the bulging seam, 12, above described.

For certain purposes of the invention, the 55 bulging seam may be formed in any known manner, but I have ascertained that by forming the same in the preferred manner above described by means of the differently curved edges, 20 and 21, on the gusset members, the desired fullness and capacity can be ob-

tained for the crotch and groin portions of the garment while maintaining a graceful form of the garment.

In adapting the garment for use as combined drawers and outer shirt, the body of the garment is provided with a neckband, 22, and is made open throughout the front to form an ordinary shirt-front closed by buttons and buttonholes as illustrated in Fig. 1.

75 What I claim as new and desire to secure by Letters Patent is:

1. In combination with a bifurcated garment having a crotch opening extending upwardly to front and rear points substantially above the crotch, a rear edge of said opening running downwardly on a straight line from said rear point, and the continuing front edge running upwardly to said front point, a gusset comprising a main portion extending throughout said opening and secured at said front and rear points, and a triangular supplementary portion adjacent the front extremity of the latter, the intersecting edges of said portions forming a reentrant angle, said last named edges being secured to said rear edge of the garment opening to cause a gathering of the gusset at the crotch, the remaining edge of said supplementary

80 portion being secured to said front edge of the garment opening.

85 2. In combination with a bifurcated garment having a crotch opening extending upwardly to front and rear points substantially above the crotch, a rear edge of said opening running downwardly on a straight line from said rear point, and the continuing front edge running upwardly to said front point, a gusset comprising a main portion 90 extending throughout said opening and secured at said front and rear points, and a triangular supplementary portion joined at one edge to the edge of said main portion adjacent the front extremity of the latter, the intersecting edges of said portions forming a reentrant angle, said last named edges being secured to said rear edge of the garment opening to cause a gathering of the gusset at the crotch, the remaining edge of said supplementary portion being secured to said front edge of the garment opening, the joined edges of said gusset sections being 95 cut on curved lines, as and for the purpose described.

100 3. In combination with a bifurcated garment having a crotch opening extending upwardly to front and rear points substantially above the crotch, a rear edge of said opening running downwardly on a straight line from said rear point, and the continuing front edge running upwardly to said front point, a gusset comprising a main portion 105 extending throughout said opening and secured at said front and rear points, and a triangular supplementary portion joined at 110 one edge to the edge of said main portion adjacent the front extremity of the latter, the intersecting edges of said portions forming a reentrant angle, said last named edges being secured to said rear edge of the garment opening to cause a gathering of the gusset at the crotch, the remaining edge of said supplementary portion being secured to said front edge of the garment opening, the joined edges of said gusset sections being 115 cut on curved lines, as and for the purpose described.

120 4. In combination with a bifurcated garment having a crotch opening extending upwardly to front and rear points substantially above the crotch, a rear edge of said opening running downwardly on a straight line from said rear point, and the continuing front edge running upwardly to said front point, a gusset comprising a main portion 125 extending throughout said opening and secured at said front and rear points, and a triangular supplementary portion joined at 130

one edge to the edge of said main portion adjacent the front extremity of the latter, the intersecting edges of said portions forming a reentrant angle, said last named edges being secured to said rear edge of the garment opening to cause a gathering of the gusset at the crotch, the remaining edge of said supplementary portion being secured to said front edge of the garment opening, the

joined edges of said gusset sections being 10 cut on curved lines, the line of said supplementary gusset section being more sharply curved than the line of said main gusset section, as and for the purpose described.

In testimony whereof, I have hereunto set 15 my hand this 27th day of July, 1926.

LILLIAN FORD TRAVER.
